DESIGN FOR A MICROPHONE STAND

Gustav F. Braun, Elizabeth, N. J., assignor to
Thomas A. Edison, Incorporated, West Orange,
N. J., a corporation of New Jersey

Application November 23, 1944, Serial No. 116,510

Term of patent 14 years

(Cl. D26—14)

To all whom it may concern:

Be it known that I, Gustav F. Braun, a citizen of the United States, residing at Elizabeth, in the county of Union and State of New Jersey, have invented a new, original, and ornamental Design for Microphone Stand, of which the following is a specification, reference being had to the accompanying drawing, forming part thereof.

Fig. 2 is an end view of the stand shown in Figure 1;

Fig. 3 is a view of the end opposite that shown in Fig. 2; and

Fig. 4 is a top view of the holder portion only of the stand.

The dominant features of my design reside in the portions shown in full lines in the drawing.

I claim:

The ornamental design for a microphone stand, as shown and described.

GUSTAV F. BRAUN.
